UNITED STATES PATENT OFFICE.

EDWARD E. CLEMENT, OF WASHINGTON, DISTRICT OF COLUMBIA, ASSIGNOR, BY
MESNE ASSIGNMENTS, TO FREDERICK C. STEVENS, OF ATTICA, NEW YORK.

TELEPHONE-EXCHANGE SYSTEM.

1,107,189.

Specification of Letters Patent. Patented Aug. 11, 1914.

Application filed November 11, 1905. Serial No. 286,887.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone exchange systems, and has for its object the improvement of such systems in the manner to be hereinafter set forth.

In attaining my object I provide a common battery exchange system, having two-wire metallic subscribers' lines, with means at each subscriber's station both to talk and to signal by making and breaking the circuit, and means at the central office controlled by the subscriber to do three things, viz., first, when the subscriber takes down his receiver his line is connected automatically to an idle connection terminal; second, the thousands and hundreds digits of the number wanted are received and indicated upon a suitable mechanism associated with said connection terminal; third, the said connection terminal, having been connected by an operator to a trunk corresponding to the number shown by the indicator, the subscriber is thus given control of a connector switch containing the terminals of 100 lines, and the last two digits of the number he sends work this connector switch 35 to select the particular line he wants.

According to one embodiment of my invention the line-terminals at central may be plugs, and according to another they may be jacks.

40 The present invention contemplates plug terminals, or what is known as a "single cord" arrangement.

Referring to the accompanying drawings, in which my invention is illustrated, Figure 1 is a diagram of the subscriber's station and line, the central office terminal apparatus therefor, and a connection terminal. Fig. 2 is a diagram of a trunk line and an automatic connector switch. Fig. 3 is a front elevation of the form of connector switch shown in diagram in Fig. 2. Fig. 4 is a bottom plan view of the switch banks and spindle, showing a wiper arm. Fig. 5 is a front view partly in section of a form of retarded relay which may be employed.

Referring now to the drawings, and particularly to Fig. 1, A is a subscriber's station having the usual transmitter T, receiver R, ringer Q, condenser C and a sending key K. Each station also has a special signal receiving device Q', polarized so that it responds only to current of one direction. From the sub-station the line-wires 1-2 pass to the central office, where they terminate in contacts n and n' of the cut-off relay N, these contacts being normally closed upon back contacts connected by wires 3 and 4 to the magnet M and the ground, respectively. The magnet, which is a part of the line relay, M, is connected on the other side through wire 5 to the main battery B, and its armature, m, which is connected to the same wire 5, controls the circuit 6 which terminates in the contact m' in the banks of the switch M'; which I shall designate the primary selector. This switch is shown as having its moving parts constantly rotated, so as to sweep a pair of contacts, m', m'', around and around over a circle of fixed contacts m' and m''. There are a number of primary selectors in an exchange, varying according to the number of lines. If, as I have found advisable, I place one hundred contacts, m' or m'' in the bank of each switch, and if I give each line multiples in ten switches, so that when that line calls and makes its contacts m' test "busy", it may be picked up by any one of the ten switches, this would mean that the total number of primary selectors would be equal to ten per cent. of all the lines coming into the exchange. This proportion may increase or decrease without affecting the merits of the invention. The switch comprises a spindle m⁸, a hub m¹², a tubular arm m¹⁴, containing an operating plug m¹⁶, and carrying the springs m⁷, m⁸, together with the banks or rings of contacts m¹, m², m³, m⁴, m⁵, m⁶, there being one of each of these contacts for each line in each primary selector switch bank. The contacts m², m⁴ are common, that is connected together, forming the terminals of the trunk-wires 7 and 8 passing to the connection terminal shown in this case as a plug P. The contacts m⁵, m⁶ are line-terminals, connected by the wires 9 and 10 to the front contacts of the cut-off relay N. Contact m' is a test contact, controlled by the line-relay, as already stated, and contact m'' is the terminal of the special holding wire 11, through which

the switch is controlled by the relay S, as will be pointed out presently. The springs m' to m^6 are mounted with interposed insulation m^{18} , in a manner well understood by those skilled in the art, so they are rigidly held in a circle around a spindle m^8 . The contacts m^5-m^8 and m^2-m^4 are provided with platinum contact points, so that when the plug m^{15} is inserted into any group to complete the talking circuit, good contacts are assured.

The spindle m^8 is supposed to be driven by means of the belt m^{11} passing over the wheel m^{10} . It may, however, be otherwise driven and controlled by the line relay m.

The plug m^{15} is connected to a soft iron core m^{10} , sliding in the tube m^{14} and controlled by the magnet windings m^{17} and m^{18} . Both of these windings are grounded on one side, and on the other side m^{17} is connected to the spring contact m^7 , while m^{18} is connected to the spring m^9 . When retracted, which it normally is, the core m^{10} takes into the notch formed in the spindle m^8 , thereby locking the arm m^{14} and all its connected parts, as well as the sleeve m^{12} , to the spindle, to be rotated thereby. The passage of current in either winding of the magnet, however, draws in the core m^{10} , projects the plug m^{15} forward through one of the back openings in the ring m^{10} , and simultaneously unlocks the arm and spring from the spindle. The arm then stops, and remains stationary as long as current is passing through the magnet winding.

The wires 7 and 8 pass to the condensers C', from which the wires 13, 14 are taken on the other side to the tip and ring, respectively, of the plug P. The sleeve of this plug is connected through cord-conductor 15 to a cut-off relay N', and thence to the battery wire 12. The idea is that when the plug P is inserted in a line or trunk-jack the cut-off relay removes all signal apparatus from connection with the cord.

The circuit 7-13, 8-14 is the same in most respects as the cord-circuit ordinarily used in common battery exchanges, that is it has on the answering end, which terminates in the primary selector M', a pair of bridged relays S, S', which jointly control the supervisory clearing-out lamp s^8 . The relay S' is on the battery through the wires 16, 17, and to line through the wires 18 and 55 8, taking current through these wires and through the cut-off relay as soon as connection is made with a line. The relay S, on the other hand, is controlled by the subscriber, either through his switch-hook H, or through the key K. When the magnet S' is energized it connects the battery wire 17 with the wire 19 leading to the armature of relay S, and also puts battery on the wire 20, normally connected through the branches 60 21 and 22 with the wires 14 and 13. The pur-

pose of this is that when the plug P is put in a trunk-jack leading to an automatic switch, the switch will first get current over both sides of the trunk, so that it will surely be restored to its zero position, before starting to pick out the line wanted. There is no communication by word of mouth in this system between the subscriber and the operator. The subscriber sets up an indicator before the operator, which gives the first half of the number of the subscriber wanted. This indicator mechanism is controlled, as well as the automatic switching mechanism by the relays S², S³, S⁴ and S⁵, and the indicators are finally cut off from the cord by the relay N'.

The relays S², S³ are so constructed as to require a considerable time for their armatures or their cores to retract after being attracted. These relays are preferably solenoids, which pull up their cores quickly, but are fitted with check valves to form dash-pots so that the cores will sink down very slowly. Solenoid S² is connected on one side to the back contact of the armature of the relay S; solenoid S³ is similarly connected to the front contact of the armature of relay S, and both solenoids are grounded on the other side. Both have their cores normally retracted. When S² is energized it pulls up 85 and momentarily closes together the springs s' and s^2 , but this produces no effect, since their circuit 23 is normally open at the armature of relay S⁵. Once up this core does not fall back again until there is a prolonged 100 break, which is when the subscriber A hangs up at the end of the conversation. The solenoid S³, on the other hand, closes together all the springs s^4 , s^5 , s^6 when it is down, and simultaneously opens the springs s^3 , s^4 .

s^6 and s^3 are the battery springs, and by this means, as will appear later, momentary impulses are sent over the wire 13, or restoring impulses are sent over both wires 13 and 14, according to the condition of relays S and S'.

During the transmission of a signal both the solenoids S², S³ remain effectively energized, as will appear from the statement of operation, the core of solenoid S² dropping 115 upon a prolonged make in the line, and the core of solenoid S³ dropping on a prolonged break in the line only.

The function of the relays S⁴ and S⁵ is to connect and disconnect the indicator magnets I, I' to the relay circuit 24 in proper sequence. The normal position of all the parts is shown in Fig. 1, the armatures of both relays being retracted, and the wire 24 being continued through the armature s^4 and 120 the wire 25 to the indicator magnet I, the other side of which is connected through wire 26 and the armature n^{10} of N' to ground. When the relay S⁴ is energized, which it is over the circuit 23 and the back 125 130

contact of its own armature s^{40} , upon the retraction of the core of the solenoid S^2 , the two armatures s^4 and s^{40} are attracted, the latter connects the winding of the relay S^4 directly to the battery wire 12, the relay being thus self locking, and the other armature connects the energizing wire 24 to the wire 27 leading to the indicator magnet I' , which is also grounded on its other side 10 through the wire 28, and the armature of the relay N' . A third armature s^{400} of the relay S^2 , or rather a third pair of contacts controlled by said relay, ground the winding of the relay S^5 when the first relay is energized and locked. The second relay is thus prepared to act, but does not so act.

In order to remove the possibility of marginal wear in these relays, a guard relay may be employed brought in at the same 20 time as the relay S^5 , and acting to open the circuit of the latter until the core of S^2 has made another excursion up and down. Or, instead of the relays S^4 and S^5 I may use a side switch of the type shown in Fig. 3, operated by one magnet as S^4 , controlled by the solenoid S^2 , and restored by another magnet as N' .

Fig. 2 shows the circuit of a trunk and of an automatic connector switch. It also shows 30 a subscriber's station A' , which, in the present case, is supposed to be the station called. Before proceeding to describe these circuits I will first describe the mechanical features of a type of switch which may be used. It 35 will be understood that I present the mechanisms shown in Figs. 3 and 4 as typical, and not as a finished embodiment of improvements. In order to render this specification clear and easily intelligible, I have taken a 40 switch of what is known as the "Strowger" or automatic electric pattern, and have arranged the actual working parts thereof in a frame, all in one plane, or nearly so, so that all of the parts can be seen, and their 45 workings understood, at a glance. This frame is indicated at F , and forms a hollow rectangle, preferably with a back plate f , upon which the parts can be mounted. In this frame is journaled a vertical spindle f^2 , 50 provided at its lower end with contact wipers f^3 and f^4 , and near its upper end with rotary and vertical ratchets f^5 and f^6 . The former of these is engaged by a pawl f^7 , of the rotary magnet V' , and the latter is engaged by the pawl f^8 of the vertical magnet V . Both the ratchets are engaged by a bifurcated detent f^9 pivoted between posts f^{10} on the plate f . This detent normally 55 holds the spindle in any position to which it is set, being maintained in engagement with the ratchets by a suitable spring, not shown. It is controlled by the release magnet V^2 , whose armature carries at its upper extremity a link v^2 , which is adapted to be 60 thrust forward when the magnet is energized.

gized, to engage a pin f^{11} on the uprising bell-crank arm of the detent f^9 , so that when the magnet V^2 is deenergized the retracting spring of the armature will pull back the detent, lifting its pawls from engagement 70 with the ratchets f^5 and f^6 , permitting a coiled spring housed within the cap f^{12} to turn the spindle back until its stop arm f^{13} strikes the stop f^{14} on the post f^{15} , when the weight of the spindle will pull it down to 75 its normal position shown in the drawing. As long as the wipers are resting on any row of contacts the spindle cannot drop, hence it must be turned back to zero in restoring.

The magnet V , which will hereinafter be called the vertical magnet, steps up the spindle in response to the first set of impulses, to bring the wipers f^3-f^4 opposite any desired 80 row of contacts; a single rotary impulse 85 then comes from the opposite side of the line and works the so-called private magnet V^3 , which pulls up its armature, and through the escapement v^3 permits the side switch lever W to move one step. This switches in 90 the rotary magnet V' , which then responds to closures of the controlling relay, shown in Fig. 2, to turn the spindle until the wipers f^3-f^4 reach the desired contacts in 95 their respective rows. When the second impulse comes from rotary side of line, the magnet V^3 steps the lever W another step, and the switch arms w , etc., then cut off the rotary magnet V' , and cut on a ringing relay which is not shown in the mechanical figures. 100 When the spindle finally returns to its normal resting position the ratchet f^5 in its downward-travel strikes the short horizontal arm of a bell-crank lever f^{16} , the long vertical arm of which presses back the lever W 105 to reset it.

At the expiration of a connection, when impulses come from both sides of the line, the circuit of the release magnet V^2 is closed, and it releases the switch spindle, as already 110 described. The relays which control and operate this switch are of ordinary type, and need no special description, but it is thought that the switch mechanism and its operation will be sufficiently understood from the foregoing, and I will therefore now proceed to trace the circuits in Fig. 2.

The jack J receives the plug P , being one of one hundred jacks, connected to trunks 115 29-30, each of which leads to a connector 120 switch whose banks contain the multiple contacts of a particular one hundred lines. Assuming, for instance, that a subscriber's 125 number is 2249: His contact for calling purposes would be No. 9 in the fourth row of the bank of the connector switch numbered 2200. The jack J of said switch would be numbered 22, and the first two digits which subscriber A would send to set up the indicators I I' in Fig. 1 would be, therefore, 22. 130

Each trunk 29-30 is supposed to be multiplied to a plurality of operator's positions, and in order to provide for a considerable load on the same connector group of lines, I 5 preferably provide 3, 5, 7 or more connector switches, trunks, and jacks J for the same one hundred lines. These being multiplied to the different positions on the manual switch-board, of course, a test is necessary to 10 ascertain if any particular trunk line is busy. This test is taken care of in the ordinary way, hence the potential of the outer ring or test thimble of the jack J is raised when the plug is inserted, and so an ordinary test 15 connection of the operator's telephone can be made, and she will simply run her plug along a row of jacks bearing the same number until she comes to an idle one of the group selected. The trunk contains a number 20 of condensers, c^2 , c^2 , which, however, I may short-circuit during conversation. It is convenient to leave these condensers where they are in the present illustration, hence I shall not describe any means for 25 cutting them out. They serve to separate the operating end of the trunk, with the vertical and rotary relays V^4 - V^5 , from the calling end, and the bridging magnets X - X' .

30 In order to control the various magnets of the switch, I provide the vertical and rotary relays V^4 - V^5 , in ground taps from the respective trunk wires 29 and 30. When the relay V^4 is energized it strikes a local circuit from ground as follows: 31-32-33-34-35 to the side switch arm w , then by a wire 36 to vertical magnet V , and to battery B by the key wire 37. After the side switch has moved a step the circuit is continued from the arm w through wire 38 to the rotary magnet V' , and then by the key wire 37 to the battery. When the side switch has moved another step the circuit from arm w is continued by wire 39 to the 40 ringing relay Y , and thence by the key wire 37 to battery. The vertical relay V^4 thus controls all of the active magnets of the switch. The rotary relay V^5 controls the side switch, and what is commonly called 45 the private magnet V^3 . Its local circuit is from ground 31-32-40-41 and 42 to battery. Each time the private magnet V^3 is energized it opens the circuit 34-35, closes the test circuit 43-44, and moves the side 50 switch arms, which are all fastened together, a single step.

The release magnet V^2 is controlled by both the vertical and rotary relays V^4 - V^5 , acting together. When the impulses come 55 from both sides of line simultaneously, and from the trunk wires 29-30, to these two relays, the release circuit is closed as follows: 31-45-46-47- V^2 -48, and battery. With the side switch in its second position, 60 that is, in position to cut on the rotary mag-

net V' , which steps the wipers around to the desired number, the next following impulse will energize magnet V^5 , then magnet V^3 , and this by closing the test circuit 43-44 will complete a circuit from the wiper f^4 , 70 to the arm w^3 , and by wires 43-44 to the release magnet V^2 and wire 48 to battery. If the line wanted is in use there will be a ground on the tip side through either the magnet X of a connector, as shown in Fig. 75 2, or through the relays S, as shown in Fig. 1. In either case the test will result in the magnet V^2 releasing the switch and preventing connection with the busy line.

On the third step of the side switch the so trunk wires 49 and 50 are connected through the arms w' w^2 to the wipers f^3 , which before that have been cut off, and the last step in the operation is ringing. It will be observed that the closed pairs of contacts 85 $y-y'$ is included in each of the conductors 49 and 50. A pair of generator contacts, y^2-y^3 , lie contiguous to these, and are connected to the ringing generator G. After the desired number has been selected, and the side switch has moved its final step, the next break produced at the subscriber's station by the key K energizes relay V^4 , which closes the circuit of the ringing relay Y, whereby the contacts $y-y'$ are separated 95 and the generator G is connected to the wanted line. I have shown the line to station A' provided with a terminal jack J' and multiple terminals J². These are shown in Fig. 2 in the banks of the switch. The wiper f^4 , with the test which I have here described, is of no importance, and may be omitted, hence the test depends upon the presence or absence of a ground on the upper wiper f^3 . The wiper f^4 is shown, however, as the banks upon which it works are 100 sometimes used for other purposes.

The operation of my system thus described is as follows: Assuming that subscriber A desires connection with subscriber 110 A', he removes his receiver R from the hook, and by so doing closes his line circuit so as to permit a flow of current from the main battery B through the relay M, which closes the local circuit 6 and puts battery on the 115 line and multiples m' in the primary selector switches M'. The first one of these switches whose arm m^9 touches the calling line terminal closes a circuit from said terminal through the arm m^9 to the coil m^{18} and ground. I may here state that I prefer to ground both coils on the frame of the switch. Upon the application of this circuit the core m^{16} is violently sucked into the solenoid, withdrawing its ends from engagement 120 with the notch in the spindle m^8 . At the same time the plug m^{15} is projected forward into the opening corresponding to the line calling, in the ring m^{19} , and between the springs m^2-m^4 , spreading the latter apart 130

and connecting them with the fixed contacts m^5 — m^6 . By this means the trunk conductors 7—8 are connected to the line extensions 9—10, and the switch arm stops. Current immediately flows from the main battery B through the cut-off relay N, by the following path: B, 16, 17, S', 18, 8, m^4 , m^8 , 10—N ground. The cut-off relay N is thereby energized and pulls in the contacts n — n' , cutting off the line relay M, and the ground 4, and connecting the line wires 1—2 onto the extensions 9—10. Current then flows out over line wire 2 to the subscriber's station, and from line wire 1, through the conductors 9 and 7, to the relay S, and ground, so that relay S pulls up instantly. This puts battery onto the contact m^8 in the switch by the following path: B—16—17—armature S'—19—armature of S,—11,— m^8 . As the arm m^7 is resting on the contact m^8 the current continues through this arm to the coil m^{17} and ground, so that as the other coil m^{18} has been cut off by the deenergization of the line relay M, the coil m^{17} will now continue to maintain the core m^{16} and the plug m^{15} in their operative positions, being controlled, it will be observed, by the relay S, which is responsive to the subscriber's actions. It should be observed, however, that this relay makes and breaks its local circuits during the process of selection of the line wanted, but the breaks are of too short duration to affect the selector solenoid, which is very slow in its movements.

The line is now connected to the trunk 7—8, and the subscriber is notified to that effect by the rising of the signal target g' , due to the reversal of current in his line; for it will be noted that when the plug m^{15} is stuck into the line jack the normal connections of battery on the line are reversed. Perceiving that he is connected, the subscriber manipulates the key K, sending two groups of breaks, corresponding in number to the first two digits of the number wanted. The first group of breaks, in rapid succession, causes corresponding movements of the armature of the relay S, which has been against its front contact, maintaining the solenoid S' in an energized condition. This solenoid will still remain effectively energized until the subscriber finally hangs up his receiver, the signaling breaks being too short to affect it; but the first movement of the armature of relay S onto its back contact will cause current to flow through the solenoid S' from the battery wire 19 through wire 24, and this solenoid will pull up quickly, and thereafter during the successive makes and breaks will also remain effectively energized, until a long make, which comes after the first group of breaks. This first group of breaks, as I have stated, moves the armature of relay S, and produces corresponding impulses of current in the wire 24, which is connected to the armature s^4 , and thence by wire 25 to indicator magnet I, and wire 26 to ground. The indicator magnet I thereupon steps around its indicator dial or drum as many steps as there are impulses. Assuming the number to be called is 2249, this would be two steps in the present case. Having sent this many breaks, the subscriber then permits the key to remain closed for a brief interval, longer than in any one break, with the result that, as the armature of the relay S remains up, the solenoid S' will continue to hold up, but the solenoid S' will permit its core to fall down, and in its travel to momentarily close the springs s' — s^2 . This puts a pulse of current from the battery on the wire 23 and through the relay S' by the following path: B—16—17—19—s—230—23— s^2 — s' —23— s^{40} —S'— n^{10} , and ground. Relay S' thereupon pulls up, locking itself by connecting the battery wire 12 to the armature s^{40} , at the same time disconnecting the latter from the battery wire 23. The armature s^4 shifts the actuating circuit 24, which is controlled by armature s of relay S, from the indicator wire 25 to the indicator wire 27. The next set of breaks which will also be two in number will therefore produce impulses in the indicator magnet I', and these will likewise step around its drum or dial and the number 2. Upon cessation of these impulses the solenoid S' will again release its core, momentarily close the springs s' — s^2 , and again send a pulse of current over the wire 23, this time through the armature s^{50} , and the relay S' to ground by the armature s^{40} , which was formerly opened. The relay S' now pulls up, locking itself by connecting the armature s^{50} with the battery wire 12, at the same time disconnecting it from the wire 23. It also connects the armature s^5 to the branch 23^a of the battery wire 23, for the purpose of putting battery through the wire 16 onto the wires 230 and 11. If this were not done, battery would be momentarily taken off of the coil m^{17} , and the control of the primary selector M' would be lost, for when the relay S' is thus energized it breaks the connection between 16 and 17, so that the subscriber will hear a click, and his signal g' if biased by a spring or weight will be drawn down out of sight. This means that he must wait a moment before transmitting further. The operator perceiving the number 22 on the indicators I—I' takes up the plug P and inserts it in the jack J (see Fig. 2) of the 22nd group, testing until she finds an idle jack of that group. As soon as this plug is inserted in the jack the circuit is completed from the battery wire 12 through the cut-off relay N' by wire 15 to the sleeve of the plug, and the outer ring of the jack and ground. The relay N' thereupon pulls up, and takes the ground off of magnets 130

I—I', and S⁴, the latter in its retraction taking the ground off of the relay S⁵, which in turn retracts its armatures, and everything passes into a condition of normal 5 disuse. The indicators I—I' remain set, however, until the operator restores them manually. I prefer to have the indicators restored in this manner, because in case of a mistake in selection of the trunk jack the 10 operator can glance at the indicators, which will still show the numbers set by the subscriber, and thus obviate any possibility of dispute.

The instant the relay S⁵ is deenergized, 15 battery is put back on the wires 16—17, the relay S' pulls up once more, and the control of the primary selector is restored, also current flows out once more over the line. The signal *g'* then rises, and the subscriber proceeds to send the last two digits of the number wanted, which are 4 and 9. The first 20 group of breaks, four in number, works the relay S, which sends impulses over the wire 24 through the springs s³ and s⁴, to the cord conductor 13, the tip of the plug P and the spring of the jack J, to the trunk conductor 29, vertical relay V⁴ and ground. The vertical relay thereupon makes and breaks the local circuits 31—32—33—34—35—36—37, 25 and steps up the switch wipers f³, to the fourth row in the bank J². As the subscriber then pauses, the solenoid S² lets down its core, and a single impulse is sent over the rotary side of line from the wire 30 to 28, s²—s¹—23—14— ring of plug, 30 second contact of jack, wire 30, rotary relay V⁶, and ground. The relay V⁶ thereupon closes the following local circuit: 31—32—40—41—42—48—B. The private magnet 35 V³ then pulls up, opens 34 and 35, and moves the side switch one step, cutting off the vertical magnet V, and cutting on the rotary magnet V'. 40

The final set of 9 breaks cause 9 impulses 45 over the cord conductor 13 and the trunk wire 29 to the relay V⁴, as before. Nine impulses therefore reach the rotary magnet V', which turns the spindle f² until the wipers f³ rest on the 9th contacts in the 50 fourth row. Next, as the subscriber pauses, comes again a single impulse over the rotary side of line 14—30 to relay V⁶. The private magnet V³ completes the test circuit 43—44, and at the same time it prepares to step the side switch its final step. I should here observe that by reason of the escapement it requires an attraction and a retraction both of the armature of the relay V² to move the side switch one step. 55 Thus, if the line wanted is busy, the final step will never be taken, for on the attraction of the armature of V², . . ., and the completion of the test circuit 43—44 thereby, a ground on the tip side of the wanted 60 line will cause the instant energization of

the release magnet V², and the switch will thereupon be returned to its normal position of disuse. Assuming that the line wanted is idle, however, no such effect is produced, the private magnet V³ retracts its armature, the circuit 34—35 is again closed as the test circuit is opened, and the side switch arms pass their final contacts. This means that arm w³ goes on to a blank point; arms w'—w² complete the trunk circuit to the 70 wipers f³, and arm w connects the wire 35 and the ringing relay wire 39. Finally, in order to ring the subscriber wanted, the calling subscriber A presses the key K an arbitrary number of times, taking care not to keep the current open a sufficient length of time to retract the core of the solenoid S³. I have timed these solenoids, so that it requires about a second for their cores to 75 fully withdraw, and I find that repeated 80 rings of from $\frac{1}{2}$ to $\frac{3}{4}$ of a second are very satisfactory. Upon finishing the conversation the subscriber hangs up, and this is necessary to release the connection. I have contemplated giving control of these 85 connections to the operator, but when the calling subscriber completes the connection himself, and does the ringing, it is not only logical, but seems to be the best practice to 90 give him control of the connection thereafter. Upon his hanging up, his line circuit is broken. Current then ceases to flow, the relay S is deenergized, the solenoid S³ loses current and permits its core to sink 95 down, and at the same time the lamp s⁸ 100 glows, being lighted by current from the wire 19. The springs s³—s⁴ are separated, and the battery spring s⁶ is put on the other two, s⁴—s⁵, which are first joined together before the battery comes on. We then have 105 a circuit from B through 16—17—19, 20—s⁶—s⁴ and s⁵ to the wires 13 and 14, 29 and 30, and through the relays V⁴—V⁵ simultaneously to ground. Both relays pull 110 up, whereupon the release circuit is closed from ground through 31—45—46—47—V²—48 and battery. The release magnet V² thereupon permits the switch to assume its normal position, and the operator perceiving the lamp s⁸ to glow, pulls the plug P, 115 whereupon the relay N' releases its armature, and all the parts are again ready for another call, the operator having reset the indicators, as previously stated.

Various modifications can be made in this 120 system, but I contemplate all changes of detail, such as specific arrangement of circuits and the like as being within the scope of my invention, and I desire my claims to be construed broadly. I believe I am the first to 125 produce what I may call a double semi-automatic system; that is, one in which the indicating calls are distributed first by machines controlled by the calling subscribers then by operators, and, finally, to wanted 130

subscribers by machines also controlled by the calling subscribers.

Having thus described my invention, what I claim and desire to secure by Letters Patent is,—

1. In a telephone exchange system, a plurality of subscribers' lines, a sending device or signal transmitter at each subscriber's station, an automatic switch for making connection with a calling subscriber's line, another automatic switch for making connection with a wanted subscriber's line, and manual connective apparatus between said switches to bring the connecting switches under control of the calling subscriber, substantially as described.

2. In a telephone exchange system, the combination of subscribers' lines, automatic answering switches and automatic connecting switches, manual connective apparatus between the switches, and means whereby a subscriber may control the switches, substantially as described.

3. In a telephone exchange system, a plurality of subscribers' lines, and connective circuits therefor each composed of three parts or lengths, one of which is automatic and controlled by the calling subscriber, the second manually controlled by an operator and the third jointly controlled by both, substantially as described.

4. In a telephone exchange system, the combination with automatic answering and connecting devices adapted to be controlled by a calling subscriber, of manual means for effecting initial selection of the group containing the wanted line, substantially as described.

5. In a telephone exchange system, subscribers' lines, a signal sending device at each subscriber's station, a primary selector switch, contacts of the lines in said switch, a trunk line to a set of connective automatic switches, which are adapted to respond to the action of the subscribers' sending devices, and manual means to connect the primary selector and the contacts of a calling line with the trunk and the connective switches, substantially as described.

6. In a telephone exchange system, subscribers' lines, primary selector switches, trunks connected to a set of automatic connective switches, whereby a calling subscriber may connect himself with any line, subscribers' contacts multiplied into the primary selector switches, and manual means for connecting any one of the primary selectors with any desired trunk, and thereby placing the associated switches under control of the calling subscriber, substantially as described.

7. In a telephone exchange system, subscribers' lines, primary selector switches, containing contacts for the lines, automatic connective switches also containing con-

tacts for the lines, means in the primary selector switches to connect the same automatically with lines when calling, manual means to connect a primary selector with a connective switch, means at the subscribers' stations to actuate said connective switches, and means to prevent more than one primary selector from becoming connected to the same line calling, substantially as described.

8. In a telephone exchange system, a plurality of subscribers' lines, a primary selector switch containing answering terminals for said lines, a set of connective switches and manual means for connecting the same to the primary selector switches, means associated with a primary selector whereby it may be controlled by a calling subscriber, and further means associated with the said primary selector and operable by the calling subscriber to control the connective switches, substantially as described.

9. In a telephone exchange system, a plurality of subscribers' lines, a plurality of primary selector switches, each containing multiple terminals of the lines, an automatic connective switch containing calling terminals of subscribers' lines, a trunk connection adapted to be manually completed from each primary selector to said connective switch, means associated with each subscriber's line to bring an idle primary selector switch into connection with the line when calling, and means associated with each primary selector brought under control of the calling subscriber by the primary selector to control the connective switch, substantially as described.

10. In an automatic telephone exchange system, a plurality of subscribers' lines, an automatic selector switch containing answering terminals for the lines, means controlled by a subscriber in calling to alter the potential on one or more of his line-terminals, controlling means for the said switch responding to such altered condition and acting to connect the switch to the line calling, an automatic connective switch with manual means whereby it may be connected to the primary selector, and means associated with the primary selector switch and controlled by the calling subscriber for controlling said connective switch, substantially as described.

11. In an automatic telephone exchange system, a plurality of subscribers' lines and a primary selector switch containing answering terminals therefor, a movable member for said switch, together with means to drive the same, so as to connect with any line having terminals therein, a centralized source of current supply for the lines, a controlling relay associated with each line, and a controlling magnet for the primary selector, an automatic connector switch to- 130

gether with manual means to connect the same to the primary selector, means at the subscribers' stations for controlling said connector switch, and multiple connecting terminals for subscribers' lines therein, substantially as described.

12. In a telephone exchange system, a multi-link central office connective circuit having an automatic switch and its trunk for the answering end, said switch adapted in response to a call over any line to automatically select and connect with said line, another automatic switch and its trunk for the calling end, said switch containing multiple terminals of the lines and adapted to be controlled by the calling subscriber so as to pick out and connect with a wanted line, and means manually controlled for connecting the two ends and thereby performing a part of the selective act in setting up a complete connection, substantially as described.

13. In a telephone exchange system, subscribers' lines each having means to make and break the metallic circuit, a central current supply, an automatic connective apparatus comprising a selecting and calling set of switches and a primary selector switch, answering line terminals in the latter with a switch member engaging the same and means to drive it, a relay associated with each line, a magnet controlled thereby and controlling the primary selector switch when the same engages the line terminals, stopping the switch thereon, controlling magnets for the selective switches, manually connected to the primary selector, and translating relays placed under the line-control by the primary selector, to control the said switch magnets, substantially as described.

14. In a telephone exchange system, the combination with a group of telephone lines extending from sub-stations to an exchange, of a plurality of link connectors at the exchange, each including a manually-operated terminal at one end of the link circuit, a traveling switch at the other end of each link circuit, means serving to arrest the operation of a traveling switch to cause it to connect its link circuit with the telephone line of a calling subscriber, and a plurality of automatic connective switches containing multiple terminals of the same lines for selecting subscribers wanted, together with a trunk connection from each of said switches to a jack adapted to receive a terminal plug of one of the cord circuits, substantially as described.

15. In a telephone exchange system, a plurality of subscribers' lines, a plurality of primary selector switches at a central office

containing answering terminals for said lines, a plug forming a switching terminal for each primary selector, a relay controlled by the subscriber to connect a primary selector with his line, a relay brought under the control of the subscriber by the primary selector switch for further controlling the said switch, signal devices associated therewith, a pair of distributing relays controlled by said second relay, and automatic connective switches having trunks terminating in jacks to coöperate with the said plugs, said connective switches being controlled through the distributing relays by the calling subscriber, substantially as described. 75 70

16. In a telephone exchange system, a plurality of line circuits, a primary selector responsive to calls over the lines, adapted to connect a calling line to an idle connective circuit, means associated with each line adapted to control a connective circuit when brought into association with its line, and means also associated with each line responsive to the action of the primary switch in effecting connection therewith, to indicate 85 the condition of the line, substantially as described. 60

17. In a telephone exchange system, a plurality of line circuits and telephone stations thereon, a primary selector switch responsive to calls over the lines adapted to connect a calling line with an idle connective circuit, means at each station for directly controlling the connective circuit after it is brought into association with the corresponding line, and a signal device at each telephone station to indicate when the line is connected, substantially as described. 90 95

18. In a telephone exchange system, a plurality of line circuits with telephone stations thereon, a primary selector switch responsive to calls over the lines adapted to connect a calling line with an idle trunk or connective circuit, a centralized source of current normally connected to the lines to furnish 100 current thereto in a definite direction, and connections from said source controlled in the operation of the primary selector switch to reverse the direction of current flow in a line when connected, together with a signal 105 device at each line station, responsive to the reversal of current, to indicate that the line is connected, substantially as described. 110

In testimony whereof I affix my signature in presence of two witnesses.

EDWARD E. CLEMENT.
